FLOATING DRY DOCK

Frederic R. Harris, New York, N. Y.

Application February 1, 1946, Serial No. 644,703

7 Claims. (Cl. 114—46)

1

My invention relates to floating dry docks, and particularly to a floating dry dock of such construction as to permit inspection, cleaning and repairs of the underwater parts thereof in a safe and expeditious manner.

The invention set forth herein is an improvement upon the floating dry dock of my Patent No. 2,325,607, granted August 3, 1943, which covers a design comprising a center section and two end sections, without enlarged side walls.

An important object of this invention to simplify the construction of the end parts or sections and to produce a center section with strong projecting or overhanging extensions of the side walls at their extremities. An advantage of this design is that the end sections, when lifting the center section for self-docking, are closer together than in the dock of my aforesaid patent, thus reducing to some extent the bending moment imposed upon the center section.

In its preferred form, the side walls of the center section are carried out, with no reduction in width, to the full length of the assembled dock. The end sections can be lowered, moved under the center section and then unwatered, thus lifting the center section by an upthrust directly upon the side walls under the overhanging extensions thereof. The side walls of the end sections are of a height only a few feet high above the pontoon deck. The side walls for the remainder of their height at the ends are integral with the center section and form the overhanging extensions aforesaid, to which the end sections are normally made fast in the regular operation of the dock for lifting and floating ships.

When it is desired to raise the center section, guide arms are attached to the end sections. Rollers on the ends of the arms engage vertical guide channels on the center section and permit the end sections to move vertically downward, while being restrained from any sidewise movement that might be induced by tidal currents, waves, etc. The end sections will be flooded to obtain a slight negative buoyancy and their descent will be restrained and controlled by cables. When the end sections have been submerged to the desired depth, the rollers at the extremities of the arms reach the bottom of vertical guide channels and in this position will be opposite the ends of horizontal guide channels on the center section connected to the vertical channels.

The end sections, with slight negative buoyancy, are then impelled under the center section. In this position, with the necessary blocking in place, the end sections are unwatered by com-

2

pressed air or by pumps. During the sinking of the end sections, they would have positive stability at all times. After the water plane is eliminated by submersion, the center of gravity of the end sections is below the center of buoyancy, thus ensuring the positive stability required.

During the lifting of the center section, the stability is first assured by the water plane of this section. Before this water plane is extinguished, the low side walls of the end section emerge thus forming water planes which provide the necessary stability to complete the operation.

A dock of this type can be constructed at one place and delivered overseas, with fully erected side walls on the end sections. The latter can be berthed on the center section. At destination, the end sections can be floated into place and the side walls thereon welded or otherwise affixed to the side walls of the center section. The presence of overhanging side walls on the center section at sea can be avoided by constructing the overhanging parts separately and stowing them between the side walls of the center section along with the end sections in the same place while enroute, and welding them in place when the voyage is ended.

In the drawings:

Figure 1 shows in plan a preferred form of my improved floating dry dock made of a center section and two end sections.

Figure 2 is a side elevation thereof with one end in lowered or submerged position.

Figure 3 is a side elevation and shows the center section docked on the end sections.

Figure 4 is an end elevation of what appears in Figure 3.

Figure 5 is an end elevation of my improved dry dock with the three main parts or sections as they appear in Figure 1.

In the drawing the same reference characters identify the same parts.

The structure disclosed herein is the preferred form of my invention but in practice changes consistent with the nature of the invention may be made without deviating from the principle underlying same.

The drydock of this invention comprises a relatively long center section 1 and two end sections 2.

The center section comprises a pontoon hull 3 and two side walls 4 which give the section a trough-like shape. All the sections are preferably provided with rounded bottoms and a central buoyancy chamber C, which divides the sections

laterally into two pumping compartments. This chamber will be of proper size, length or width.

Each of the side walls 4 has a projecting or overhanging portion 5 at each end; these portions extending beyond the extremities of the hull 3. These extensions 5 are of the same transverse thickness as the walls 4, and have their lower faces a little above the level of the deck 6 of the hull 3. They can be built separately and welded or otherwise affixed to the side walls 4. The side walls 7 of the end sections are relatively low in height; the end sections 2 are about as long as the extensions 5; and when the walls 7 are under and in contact with the extensions 5 the center and end sections float on the water at substantially the same level. A hinged outrigger or work platform 8 is preferably attached to each end section.

On the outboard faces of the main side walls 4 are guide channels 9, just above the chines 10. These channels have portions that are horizontal and run from the ends of the hull 3 along the walls 4 towards the middle of the dock; and these horizontal portions connect with vertical portions at the ends of the hull that run up towards the tops of the walls 4. At the adjacent ends the sections 2 are equipped with arms 11 carrying rollers 12 that engage the channels 9.

On the inboard faces of the overhanging projections 5 of the side walls 4 are similar guide channels 13 having horizontal portions running along the lower edges of the projections 5, with vertical connecting portions at the extremities of the overhangs 5 running up to the tops of the latter. On the adjacent corners of the ends 2, adjacent the inboard faces of the walls 7 are posts 14 on which are mounted rollers 12 which enter the guide channels 13.

On the tops of the overhanging extensions 5 at the ends, and at the ends of the pontoon deck 6 in the middle are bearings for guide pulleys 15 over which lines are passed to each end section to be secured thereto at three points. The lines over these pulleys are kept taut by a suitable means to maintain the control of the ends 2 as they are sunk or raised.

For the usual operation of raising ships, the ends 2 are attached to the center 1 in the positions shown in Figures 1 and 5 and at the left of Figure 2. The sections are secured together in any suitable way and the walls 7 may be affixed to the overhangs 5. The dock is then sunk and pumped out as one piece. The rollers 12 are then all at the tops of the vertical portions of the channels 9 and 13, or the members 11 and 14 with the rollers 12 may at this time be dismounted.

To dock the center 1, the ends are flooded and sunk to the position shown at the right of Figure 2. The members 11 and 14 are first mounted in their respective positions. The rollers on the members 11 and 14 now drop to the level of the horizontal parts of the guide channels 9 and 13. The ends 2 are now impelled under the extremities of the center 1 as shown on Figure 3. When pumped out the ends 2 lift the center 1 till its bottom is cut of water. At this time the tops of the walls 7 on the ends 2 carry sloping blocks 17 to engage the round bottom of the center 1 along the sides thereof, and the middle of the pontoon hull 3 rests on keel blocks 18.

When moving under the center 1 the ends 2 must of course be sunk far enough in the water for the blocks 17 to clear the bottom 7 of the center. Therefore the horizontal portions of the

channels 9 and 13 are low enough on the center 1 and the arms 11 and posts 14 are of sufficient length. But when the ends are under the center as far as the horizontal portions of the channels 9 and 13 permit, the ends must be allowed to rise a little till the blocks 17 make contact with the center part 1. For this purpose the adjacent or the inner ends of the horizontal portions of the channels 9 and 13 have upward extending recesses shown at 9' and 13' respectively to allow upward movement of the arms 11 and posts 14 till the blocks 17 engage the round bottom of the center 1.

Of course the guide channels can be disposed elsewhere than as shown in any suitable relation and the same mode of operation and results obtained.

To dock the ends 2, they are freed from the center 1 and the latter is sunk. The ends are shorter than the distance between the walls 4 of the center 1. With the center 1 submerged the ends are turned and floated sidewise into the center 1 between the walls 4, as in the dock of my prior patent aforesaid. Then the center is pumped out and raised and the ends are raised with it. They come to rest on similar blocks and they can be inspected, cleaned and repaired at any point, including their bottoms.

In this position, too, the dock can make a voyage, the center 1 carrying the ends 2 and being the only part afloat on the water. The overhanging projections 5 might be detached at this time and stowed on the pontoon 3 along with the ends 2, being bolted or otherwise secured in place and be affixed in position to the walls 4 when the voyage is completed.

Having described my invention, what I claim as new is:

1. A floating dry dock having sections comprising a center and ends, and means comprising channels of predetermined length on one section, and parts on the remaining sections engaging said channels for permitting limited relative movement of said center and ends in both a horizontal and vertical direction.

2. The dry dock of claim 1, wherein said channels have both horizontal and vertical portions.

3. The dry dock according to claim 1, wherein the center carries the channels and said parts are on the ends, and have rollers to engage said channels.

4. In a floating dry dock, a center section with a deck and main side walls thereon having overhanging extensions projecting beyond the extremities of said center section, said extensions being above said deck, and end sections having low side walls thereon, to underlie and engage the lower faces of said extensions, one of said sections having channels of predetermined length, and the other sections having parts engaging said channels to permit limited relative motions of said center and end sections in both a horizontal and vertical direction.

5. The floating dry dock according to claim 4, wherein said center section has said channels and the latter have vertical and horizontal portions and the end sections bear the parts which engage said channels.

6. The dry dock according to claim 4, wherein the center section has said channels, and the latter are disposed on the inboard faces of said extensions and the outboard faces of the remainder of said walls, and said parts are on the end sections and engage all said channels.

7. The floating dry dock according to claim 4, wherein said center section has said channels, which are horizontal, with vertical portions at one extremity and upward extending recesses at their opposite extremities, said channels being on the inboard faces of the extensions and the outboard faces of the remainder of said walls, and said parts are on the end sections and engage said channels.
